BUILDING CORNER CONSTRUCTION AND UNITS THEREFOR

John H. Gibson, Cleveland, Ohio, assignor to
The Weaver-Wall Company, Cleveland, Ohio,
a corporation of Ohio

Application November 24, 1930, Serial No. 497,652

18 Claims. (Cl. 20--5)

This invention relates to wall coverings for building purposes and more particularly to building corner construction and corner pieces adapted to be used with siding strips of weather proof material to form a wall covering having the appearance of a brick wall. By cutting material, such as asphalt impregnated felt covered with granular slate or the like, into strips of proper shape and color, and attaching them to the wall of a building it is possible to simulate closely the appearance of a brick wall.

In constructing walls of this type however, considerable difficulty has been experienced in making the corners of the building appear exactly as they would appear in actual brick construction and, so far as I am aware, no satisfactory solution of this problem has been reached prior to the present invention.

It is among the objects of my invention therefore, to provide a corner piece which may be used in connection with siding strips and which will give a perfect imitation of a brick corner.

Another object of my invention is to provide a corner piece which is properly formed to cover the corner of a building and form a neat joint with the adjacent overlapping siding strips.

Another object of my invention is the provision of a corner piece which is preformed and which has sufficient strength to hold its form while being shipped and while being applied to a building.

Another object of my invention is the provision of a corner piece which may be economically manufactured and quickly and easily applied to a building.

A further object of my invention is the provision of a corner piece which is adapted to be made in rights and lefts which, when placed alternately on the corner of a building give a perfect representation of a brick wall with mortar between the bricks.

Other objects of my invention will appear from the following description of one form thereof, reference being had to the accompanying drawing in which:

Fig. 1 is a perspective view of a building corner to which my corner pieces are applied, the walls of the building being covered with brick resembling strip siding;

Fig. 2 is a detached developed view of one of my corner pieces;

Fig. 3 is a section taken on line 3--3 of Fig. 2;

Fig. 4 is a perspective view generally similar to Fig. 1 but showing in detail the arrangement of the corner pieces and the adjacent siding strips;

Fig. 5 is an end view of the structure shown in Fig. 4;

Fig. 6 is a section taken on line 6--6 of Fig. 5.

The walls 1 and 2 shown in Fig. 1 are covered with overlapping strips of siding material. This material is commonly a felt base impregnated with asphalt and having bands of granular slate and sand or the like, rolled into its outer surface. By cutting vertically extending slots in these strips and arranging the strips in staggered relation, it is possible to construct a wall which closely duplicates the appearance of a brick wall. In building up a siding strip covered wall of this type, it is necessary to complete the illusion of a brick wall, to provide corner pieces which are the length of the side of a brick on one side and the length of the end of the brick on the other side. Corner pieces 3 may be considered as left hand pieces as they have their long sides on the wall 1 while corner pieces 4 may be considered as right hand pieces, the long sides of pieces 4 being on the wall 2 (Fig. 1). In building up the corner successive right and left hand pieces are used, thus securing a perfect brick wall corner representation as illustrated in Fig. 1.

In manufacturing the corner pieces shown in the drawing, I prefer first to impregnate the felt base with fluid asphalt and then apply the outer coating of granular material in any desired and suitable manner. This coating may consist of a bottom band 5 of relatively coarse brick resembling slate, a middle band 6 of relatively fine mortar resembling sand or the like, and a narrow top band 7 of granular slate.

The blank from which a left hand corner piece 3 is formed, is illustrated by dot and dash lines in Fig. 2. This view shows the corner piece before it has been bent into its final angular shape. The slot 8 extends downwardly from the edge 9 of the piece and serves to facilitate bending thereof. This slot also permits the piece to closely engage the corner of the building when applied thereto. As seen from this view the piece is not of a rectangular shape but has a portion cut out at 10 and a corner cut off at 11 for purposes which will be described later.

As is best seen in Figs. 3, 5 and 6, a portion of the piece above the band 5 and at the bend in the material is offset rearwardly of the rest of the piece as shown at 12. This offset permits the alternate right and left hand corner pieces to be applied to the wall in overlapping relation with their top and bottom edges lying in a horizontal plane. This construction eliminates the necessity of cutting the top and bottom edges of the

long sides of the corner pieces at an angle to the top and bottom edges of the short sides of the corner pieces so that they will lie in a horizontal plane when bent and applied to the wall corner 5 in overlapping relation. The offset 12 is greatest at the bend of the piece and preferably tapers off on both sides of the bend until it joins the main body of the corner piece.

When the corner pieces are applied to a wall, a 10 substantially straight vertical line 13 is formed at the corner as the offset 12 is of a depth equal to the thickness of the material from which the pieces are made. The vertical position of the bottom of the offset portion 12 is such that when the 15 pieces are laid up in overlapping relation with the bottom edge of one piece placed at the bottom of the offset of the piece immediately below, a mortar line 14 (Fig. 5) of proper width is exposed on the lower piece.

20 By cutting off the corner 11 and removing the upper right hand part of the generally rectangular outline of the corner piece as outlined in dot and dash lines in Fig. 2, it is possible to nail the pieces to the wall in overlapping relation and 25 have the corner of the building covered by an even double thickness layer of material as shown in Fig. 6. By cutting away the pieces in this manner the offset portion of each piece lies flat against the building wall when the pieces are 30 applied.

The cutting off of corner 11 and shaping the piece on an angle as shown at 10 prevents objectionable bulging of the superimposed corner piece which might result if there were rectangular corners at these points.

35 In manufacturing corner pieces of this type, I prefer to form the offset 12 and bend the pieces into their angular shape in a single operation which may be done at the same time as the cutting of the piece to shape. These operations are 40 all preferably done while the asphalt is still soft as this permits the bending to be done without cracking of the material and forms a corner piece which will hold its shape after the asphalt 45 hardens.

Other arrangements of the bands of brick resembling and mortar resembling materials may be made on the sheets without departing from the spirit of my invention, as it may in some 50 cases be desired to use the corner pieces of this type with strips of types other than those shown in the accompanying drawing.

55 It will also be understood that, although I have described particularly a left hand corner piece, the right hand pieces are the same in all respects except that the positions of the parts are transposed.

Although I have described the illustrated embodiment of my invention in some detail, it will 60 be understood by those skilled in the art to which it appertains that modifications and variations thereof may be made without departing from the spirit of my invention and therefore I do not wish to be limited other than by the appended claims.

65 1. A corner piece of asphalt impregnated felt of substantially uniform thickness throughout having a long side and a short side angularly disposed relative to said long side, said long side and said short side being joined for a portion of their 70 width extending upwardly from their lower edges and separated for the remainder of their widths, said separated portions of said sides being offset relative to said joined portion.

75 2. A corner piece comprising a strip of asphalt impregnated felt or the like of substantially uni-

form thickness bent into angular form having a long side and a short side and having a slot extending downwardly from the top edge at the bend.

3. A corner piece of the class described and of substantially uniform thickness, having angularly disposed sides, said sides being joined at their bottom edges and spaced at their top edges and having offset portions, said offset portions being offset substantially the thickness of the material 10 of the corner piece.

4. A corner piece comprising a sheet of material having a brick resembling surface at its lower edge and a strip of mortar resembling material above said brick resembling surface, said sheet being formed into angularly disposed portions joined together throughout the width of said brick resembling portion and separated from the top edge down to a point a distance equal at least to the thickness of a mortar line above 20 the top edge of said brick resembling surface.

5. A corner piece comprising a strip of material of substantially uniform thickness throughout bent into angular form and having a portion of said strip extending around the bend offset 25 from the body of the piece substantially the thickness of the material.

6. A bent corner piece comprising a long side and a short side angularly disposed thereto said sides being connected for substantially the lower 30 half of their width and separated for the remainder of their width and having offset portions adjacent the bend in said piece, said portions being offset the greatest amount at the bend of the piece and tapering outwardly therefrom.

35 7. In building construction, a corner comprising right and left hand corner pieces arranged in alternate overlapping relation, each piece being of substantially uniform thickness throughout 40 and having an offset portion extending around the corner and each of said offset portions being overlapped by the superimposed corner piece.

8. In building construction, a corner having the appearance of a brick wall corner comprising a plurality of corner pieces of material of substantially uniform thickness throughout and having brick resembling parts and mortar resembling parts, a portion of said mortar resembling parts extending around the bend of each corner piece 45 and being offset at the corner substantially the thickness of the material of the piece, said corner pieces being arranged in overlapping relation with their bottom edges substantially horizontal and each of said offset portions lying parallel with the building wall and being covered by the superimposed corner piece.

50 9. A corner piece of asphalt impregnated felt of substantially uniform thickness throughout comprising two angularly disposed sides, one of said sides having a portion resembling the side of a brick and the other of said sides having a portion resembling the end of a brick and each of said sides having a mortar resembling portion adjacent the brick resembling portion, said sides being joined at the vertex of the angle 55 therebetween and having offsets in their mortar resembling portions, said offsets extending to and being of a depth at said vertex equal to the thickness of the material.

70 10. A corner piece of asphalt impregnated felt comprising joined angularly disposed sides of substantially uniform thickness throughout and having an offset portion extending outwardly on both said sides from the vertex of the angle 75 therebetween said offset portion being offset

substantially the thickness of the material of the corner piece and having its lower edge substantially parallel to the bottom edges of said sides.

11. A corner piece of substantially uniform thickness having angularly disposed sides and having brick and mortar representations thereon, said sides having offset portions extending downwardly from the top and a slot extending downwardly at the intersecting line of the sides to a point above the lower edge of said offset portions.

12. A corner piece of the class described having a long side and a short side angularly disposed thereto, said sides having offset portions adjacent the bend in said piece, said portions being offset the greatest amount at the bend of the piece and tapering outwardly therefrom.

13. A bent corner piece of material having substantially the properties of asphalt impregnated felt and being of uniform thickness throughout and having brick resembling parts and mortar resembling parts, said mortar resembling parts extending around the bend of said corner piece and being offset at the corner substantially the thickness of the material of the piece.

14. A corner piece of substantially uniform thickness having angularly disposed sides and having brick and mortar representations thereon, said sides having offset portions extending downwardly from the top, said portions being offset substantially the thickness of the material of the corner piece.

15. A surface covering for buildings composed of flexible roofing material having outer surfaces

lying at dihedral angles to each other, including strips of material which extend around the dihedral angle, portions of the strip being slit or kerfed, said kerfs being all positioned at the apex of the dihedral angle.

16. A surface covering for buildings composed of flexible roofing material having outer surfaces lying at dihedral angles to each other including overlapping strips of material certain of which strips extend around the dihedral angle, the strips extending around the angle being slit or kerfed down from the upper edge, said kerfs being all positioned at the apex of the dihedral angle.

17. A surface covering for the outer surfaces of buildings composed of flexible roofing material having outer surfaces lying at dihedral angles to each other including overlapping strips of said material certain of which strips extend around the dihedral angle, the covered portions of the strips extending around the angle being slit or kerfed, the kerfs in said elements being offset from the middle, said kerfs being all positioned at the apex of the dihedral angle, whereby each element presents a greater exposure on one side of the apex of the dihedral angle than on the other.

18. A covering unit formed of flexible material and adapted to be bent around either an inside or an outside corner, said unit being rectangular in shape and having a slot extending from an edge inwardly whereby the upper portion of said unit will be foreshortened in being bent around the corner.
